CONVERTIBLE PNEUMATIC CLEANING APPARATUS

Charles H. Taylor, Springfield, Mass., assignor to Westinghouse Electric Corporation, East Pittsburgh, Pa., a corporation of Pennsylvania

Application September 27, 1943, Serial No. 503,915

8 Claims. (Cl. 15—9)

1

My invention relates to a suction cleaner. More particularly it relates to a suction cleaner in which a suction nozzle for cleaning the floor is carried by the casing that houses the suction cleaning device or fan. In cleaning the floor or floor covering, the casing is propelled over the surface to be cleaned and this manner of use is referred to herein as floor-nozzle cleaning. The cleaner is also provided with an attachment hose connectible at one end to the suction side of the fan and having attachments connected at its other end. Use of the cleaner with the suction applied to the hose is referred to herein as attachment cleaning or attachment suction cleaning. The attachment hose is also connectible to the discharge side of the fan to blow air through the hose and any attachment that may be connected to the other end, and such use is referred to herein as attachment blowing.

One object of my invention is to produce an improved suction cleaner of the type set forth.

A further object of my invention is to produce an improved converting mechanism for a cleaner of the type set forth, which is easy to manipulate.

A still further object of my invention is to produce a suction cleaner of the type set forth in which the converting mechanism is built into and forms part of the cleaner construction, while the means for actuating the converting mechanism from one operative position to the other is carried by the inner end of an attachment hose.

Still more particularly, my invention relates to a suction cleaner, of the type set forth, that is readily convertible from one type of cleaning to another.

A still further object of my invention is to produce a converting mechanism which is moved from one operating position to another by a simple endwise movement of the inner end of said attachment hose.

A still further object of my invention is to produce an improved construction which includes locking means for retaining said converting mechanism against unintended movement from any operative position to which it may have been adjusted, together with means for insuring the return of the converting mechanism to the position it occupies while the cleaner is used for floor-nozzle cleaning before the attachment hose can be disconnected from the cleaner.

A still further object of my invention is to produce a convertible cleaner which includes means for preventing conversion from floor-nozzle cleaning to attachment suction cleaning or blowing, unless the brush roll has first been

2

raised from contact with the surface being cleaned, together with means for retaining said brush roll in its raised position until the cleaner has been reconverted to the floor-nozzle cleaning position.

These and other objects are effected by my invention as will be apparent from the following description and claims taken in connection with the accompanying drawings, forming a part of this application, in which:

Fig. 1 is a view partly in elevation and partly in vertical section of a suction cleaner embodying my invention;

Fig. 2 is a fragmentary enlarged sectional view on line II—II of Fig. 1;

Fig. 3 is a perspective view of a guiding and latching mechanism forming part of my invention;

Fig. 4 is a view similar to Fig. 1 showing, in solid lines, the position of the parts when the cleaner is converted to attachment suction cleaning and showing in dotted lines the position of the parts when the cleaner is converted to attachment blowing;

Fig. 5 is an enlarged, fragmentary view in horizontal section showing the first step in converting the cleaner from floor-nozzle cleaning to attachment suction cleaning or attachment blowing;

Fig. 6 is a view similar to Fig. 5, showing the position of the parts after the cleaner is converted to attachment suction cleaning;

Fig. 7 is an enlarged section taken substantially on line VII—VII of Fig. 5;

Fig. 8 is a section on line VIII—VIII of Fig. 7; Fig. 9 is a fragmentary and diagrammatic view, partly in vertical section and partly in elevation, of a cleaner embodying a modified form of my invention;

Fig. 10 is an enlarged fragmentary horizontal section, showing the position of the parts when the cleaner is in floor-nozzle cleaning position;

Fig. 11 is a fragmentary horizontal section, showing the position of the parts when the cleaner is converted to attachment blowing;

Fig. 12 is an enlarged view of the right-hand portion of Fig. 11;

Fig. 13 is an enlarged fragmentary vertical sectional view, showing a still further modified form of my invention; and

Fig. 14 is a section on line XIV—XIV of Fig.

13.

Referring to the drawings in detail and more particularly to Fig. 1, I show a suction cleaner mounted on wheels 22 and provided with a

55 20,

pivoted propelling handle 24. The cleaner 20 comprises a floor cleaning nozzle 26 which is connected by a passage 28 and a throat 30 to a filter bag compartment 32. In the nozzle 26 is mounted a brush roll 34.

In the dust bag compartment 32 is a filter bag 36, the inlet end of which communicates with the throat 30. The filter bag 36 may be removed for emptying through an opening in the casing (not shown). The cleaner also includes a compartment 40 which is provided with an outlet 44 formed in a wall 46 thereof. The opening 44 communicates with an opening 50 in a pendant wall 52. The opening 50 communicates with the atmosphere through an opening 54 formed in the outer casing of the cleaner.

The cleaner also includes a suction-creating device 42 which is disposed in the compartment 40. The suction-creating device is preferably of the multi-stage type and is rotatable about a horizontal axis 43. The compartment 32 communicates with the inlet of the suction-creating device through an opening which is not shown but which is indicated by the broken line arrow in Fig. 1.

In order to render the cleaner thus far described convertible to attachment suction cleaning in an on-the-floor or off-the-floor manner, or to attachment blowing, I provide a passage 56 which is normally closed off from the passage 28 and the throat 30, by a valve 58. The valve 58 is biased by a spring 60 into position closing the passage 56. In the passage 56 is positioned a slide 62, which includes a reduced inner portion 64 having one side wall extended to form a finger 66, and an outer enlarged portion 68 separated from the reduced portion 64 by a shoulder 70. The slide 62 also carries a shutter 74 which, when the slide is in its outermost position, is adapted to abut against the wall 52 to close the opening 50. The abutment of the shutter 74 against the wall 52 limits the movement of the slide, to the right as viewed in Fig. 1, and thus prevents withdrawal of the slide from the passage 56.

The enlarged portion 68 of the slide 62 is provided with an opening 76 formed in a side wall 78, the outer end of which is beveled to form a slanting surface 80. As shown in Fig. 7, the lower portion 82 of the side wall 78 is made thinner than the upper portion thereof, thus providing an outer surface offset inwardly from that of the upper portion.

The slide 62 is adapted to assume one position when the cleaner is used for floor-nozzle cleaning, a second position when the cleaner is used for attachment suction cleaning, and a third position when the cleaner is used for attachment blowing. In order to actuate the slide 62 and in order detachably to connect it to an attachment hose, I use an adapter 86 (Fig. 6) which comprises an elongated conduit terminating in a coupling 90 to which is connected one end of an attachment hose 92 (Fig. 4), the other end of which carries a suitable cleaning tool (not shown). On the top wall 94 of the adapter 86 is mounted a lever 96 which is fulcrumed at 98 and biased in the direction of the arrows 99 by a spring 100. The lever 96 terminates at one end thereof in a pendant latch member 102 and at the other end thereof in a pendant grip portion 104. The pendant latch member 102 is adapted to be withdrawn, against the action of the spring 100, into a seat or recess 106 formed in a side wall 108 of the adapter 86. The lever and spring as-

sembly are preferably concealed by a cover 110 secured to the top wall 94 by screws 112. In several views, the cover 110 is broken away so as to expose the lever and spring construction. When the adapter 86 is inserted into the slide 62, the end 114 thereof abuts against the shoulder 70.

In order to retain the slide 62 against accidental displacement while the cleaner is used for floor-nozzle cleaning, I provide a latching device 116 which is shown detached in Fig. 3. This device comprises a U-shaped member having side walls 118 and 120, there being a notch 122 in the side wall 118 and spaced notches or openings 124 and 126 in the wall 120. The side walls 118 and 120 define an elongated trough in which the lower end of the pendant latch 102 is adapted to move, as shown in Fig. 7. The side wall 118 is provided with a deflected guide extension 127 which, when the cleaner is in the floor-nozzle cleaning position, forms a continuation of the slanting surface 80 (see Figs. 2 and 10) to guide and facilitate the insertion of the adapter 86 into the slide 62. The wall 120 is extended to form a shelf member 128 on which a latch member 130 is pivoted at 131. The latch member 130 is biased by a spring 132 in the direction of the arrow 133 (Fig. 3). One end of the spring 132 is conveniently anchored by a post 134 struck up from the top wall or shelf 128. The latching device 116 is rigidly secured to the cleaner body in operative relation to the slide 62 and the adapter 86 by bolts or rivets 136 engaging a boss or other fixed portion of the body of the cleaner to one side of the passage 56.

The fan motor compartment 40 is provided with a bottom opening 138 which, in the position of the cleaner illustrated in Fig. 1, is closed by the top wall of the slide 62, but which, in the position of the cleaner illustrated in dotted lines in Fig. 4, is uncovered and communicates with the open end of the slide 62 for a purpose hereinafter set forth.

The brush roll 34 is carried by an arm 140 which is biased upwardly by a spring 142. One end of the arm 140 is pivoted at 144 to a portion of the nozzle wall and the other end thereof is pivoted to the core of a solenoid 146. The solenoid 146 is connected by wires 148 to a switch 150. The switch 150 includes a button 152 which is normally biased by a spring (not shown) to close the circuit and energize the solenoid 146. When energized, the solenoid 146 pulls the brush roll down against action of the spring 142 and into contact with the surface being cleaned.

Coacting with the switch button 152 and with the latch 130 is a lever 154, pivoted at 156 to a suitable fixed portion of the cleaner body. The lever 154 is normally biased by a spring 158 so as to bring the lower end 160 of the lever 154 into engagement with the latch 130, and out of contact with the button 152, as shown in Fig. 2. The upper end 162 of the lever 154 is adapted to be engaged by the lower portion of the handle 24, or by an extension 164 carried by the lower portion of the handle, and to be moved against the action of the spring 158 from the position shown in Fig. 2 into the position shown in Fig. 5, in which the lower end 160 of the lever 154 has been moved out of engagement with the latch 130 and into engagement with the button 152, to open the switch 150 and thus deenergize the solenoid 146. The switch 150 is so constructed and arranged that the button 152 is unaffected by movement of the handle 24 in its normal range of operation (Fig. 1).

Operation—Figs. 1 and 2

In the position shown in Figs. 1 and 2, the cleaner is adjusted for floor cleaning through the nozzle 26. In this position, the slide 62 is in a central or intermediate position so that its end 66 is out of contact with the valve member 58 which is biased by the spring 60 into the position closing the passage 56 from the throat 30 and the suction-creating device 42. Likewise, the shutter 74 does not close the opening 50, and the opening 138 is closed by the top wall of the slide 62. The switch 150 is closed, the solenoid 146 is energized and the brush roll 34 is in contact with the surface being cleaned. In this position, the air drawn by the suction device 42 travels through the nozzle 26, passage 28, throat 30, dust bag 36, into the fan compartment 40 through and out the openings 44, 50 and 54. The slide 62 is retained in this position by the latch 130 engaging in the opening 76 (Fig. 2). The latch 130 is locked against unintended movement by the lower end 160 of the lever 154, as shown in Fig. 2. If, in this position of the parts, the adapter 86 is inserted into the slide 62, the adapter 86 cannot be locked in place, and hence the operator will be apprised of the fact that the cleaner is adjusted for floor-nozzle cleaning only.

Conversion

When it is desired to convert the cleaner to attachment suction or attachment blowing, the cleaner handle 24 is moved from the acute angle position it occupies during floor-nozzle cleaning (Fig. 1), to a vertical or slightly over-vertical position (Fig. 4). In this position, the arm 164 engages the lever 154 and moves its lower end 160 from the position shown in Fig. 2, in which it locks the latch 130 against movement and in which position it is out of engagement with the button 152 of the normally closed switch 150, into the position shown in Figs. 5 and 6 in which the end 160 of the lever 154 is disengaged from the latch 130 and in which it engages the button 152 and opens the switch 150 to deenergize the solenoid 146. This insures the raising of the brush 34 by the spring 142, out of contact with the surface being cleaned before the cleaner can be converted. The adapter 86 is now inserted into the slide 62 in the direction of the arrow 167 in Fig. 2.

When the latch 102 reaches a position in registration with the latch 130, the latch 102, being biased outwardly by the spring 100 which is stronger than the spring 132, pushes the latch 130 out of the opening 76 (Fig. 5). The slide 62 is now free of the latch 130, and the slide 62 and the adapter 86 are now latched together by engagement of the horizontal portion 168 of the lever 96 with the walls of the opening 76, and are free to move as a unit with the lower portion of the latch 102 sliding in the trough provided between the walls 118 and 120.

Attachment suction cleaning

If it is desired to use the cleaner for attachment suction cleaning, the slide 62 and adapter 86 are moved to the innermost position, shown in Figs. 4 and 6. In this position, the finger 66 of the slide 62 actuates the valve 58 from the position shown in Fig. 1 to that shown in Fig. 4, in which the floor nozzle 26 is cut off from the throat 30 and in which the throat 30 is now in communication with the interior of the passage 56, slide 62, adapter 86 and the attachment hose 92. In this position, the latch 102 is engaged in

the notch 124 to prevent accidental movement of the slide 62 and adapter 86. The air is now drawn into the dust bag 36 through the attachment hose 92 and is discharged through the openings 44, 50 and 54, as shown by the solid arrows in Fig. 4.

Attachment blowing

Assuming that it is desired to convert the cleaner from attachment suction cleaning to attachment blowing, it is merely necessary to press the grip portion 104 of the lever 96 inwardly to retract the latch 102 from the opening 124. Thereupon, the lower portion of the latch 102 can slide freely in the trough between the walls 118 and 120 of the latching device 116, and the interlocked slide 62 and adapter 86 are moved outwardly or to the position shown in dotted lines in Fig. 4, and in full lines in Figs. 11 and 12, until the shutter 74 closes the opening 50 and thus limits the movement of the slide 62 and adapter 86. The opening 138 is uncovered and communicates with the passage 56, and the valve 58 closes the passage 56 from the throat 30. Air is now drawn by the suction device 42, through the nozzle 26, in the direction of the dotted arrows in Fig. 4, and since the discharge opening 50 is closed by the shutter 74, the filtered air is discharged through the opening 138 into the passage 56 and through the slide 62, the adapter 86 and the attachment hose 92. In this position, the latch 102 engages the opening 126 in the latching device 116 to prevent displacement of the slide 62 and adapter 86.

If the cleaner is to be converted directly from floor cleaning to attachment blowing, the slide 62 and adapter 86 are inserted as shown in Fig. 5, but instead of being moved inwardly to the position shown in Fig. 6, they are moved outwardly to the position shown in dotted lines in Fig. 4 and in solid lines in Figs. 11 and 12.

To reconvert the cleaner from either attachment suction or attachment blowing to floor-nozzle cleaning, the latch 102 is withdrawn from the opening 124 or 126 and the slide and adapter are moved back as a unit to the central position illustrated in Fig. 5, in which the latch 102 may be retracted through the openings 122 and 76 by pressure on the grip 104 against action of the spring 100. As the latch 102 is retracted through the openings 122 and 76, the latch 130 is biased by the spring 132 into the opening 76 in the wall 78 of the slide to lock the latter in the intermediate or floor-nozzle cleaning position. The adapter 86 may now be withdrawn from the slide 62.

It is to be noted that the construction is such that it is impossible for the operator to withdraw the adapter 86 without first bringing the adapter 86 and the slide 62 to the intermediate or floor cleaning position of Fig. 5. This is so for the reason that the latch 102 extends through the opening 76 in the slide 62, and the wall 118 prevents withdrawal of the latch through said opening until the adapter and the slide are brought to the intermediate position in which the latch may be withdrawn through the notch 122. It will also be noted that simultaneously with the retraction of the latch 102 from the opening 76, the latch 130 engages the opening 76 to lock the slide 62 in floor cleaning position.

It will also be seen that once the handle is raised to permit conversion as above explained, and once the latch 102 has displaced the latch 130, the displaced latch 130 will maintain the lever 154 in the position shown in Figs. 5 and 6,

in which the lower end 168 of the lever 154 keeps the switch 150 open, regardless of the position of the handle 24, until the slide 62 and adapter 86 have been returned to their intermediate position and the adapter 86 has been withdrawn from the slide 62. This insures that the brush roll 34 will remain raised out of contact with the surface on which the cleaner rests, as long as the cleaner is used for other than floor-nozzle cleaning.

I have thus devised a suction cleaner which is 10 readily convertible to attachment suction cleaning or attachment blowing by insertion of an adapter attached to one end of an attachment hose, and by merely moving the adapter to an extreme inner or extreme outer position to adjust 15 the cleaner to attachment suction or attachment blowing, respectively.

Figs. 9 to 12

In Figs. 9 to 12, I show a modified form of construction in which the spring 142 and the solenoid 146 are omitted and in which the brush roll 34 is biased downwardly into contact with the surface being cleaned, by a spring 169 acting upon a collar 170 fixed on an extension arm 172 of a 20 bracket 174 pivoted at 176 and supporting the brush roll 34. A rod or wire 178 is connected at one end to the bracket 174 at 180, and is secured at 182 to a yoke 184 pivoted at 186. The other end of the rod 178 is secured to a pin 188, which is movable in a slot 190. The pin 188 is retained against tilting or withdrawal from the slot 190 by any well-known means. The outer end of the pin 188 carries a yoke 194, which seats and guides the lower end of the handle 24 or of the extension 35 164 carried by the lower portion of the handle.

Operation—Figs. 9 to 12

When the handle is within its normal range of operation, or substantially below vertical, the arm 164 is out of contact with the pin 188 as shown in Fig. 10. In this position, the spring 169 biases the brush roll 34 downwardly into contact with the surface to be cleaned, and the end 192 of the pin 188 is in direct alignment with a lug 194a carried by the latch 130. It is obvious that with the parts as shown in Fig. 10, the latch 130 cannot be disengaged from the opening 76 in the slide 62, so that the slide 62 is immovable, the latch 102 on the adapter 86 cannot enter the opening 76 and cannot be latched to the slide 62. In other words, the cleaner cannot be converted.

In order to convert the cleaner, it is necessary to raise the handle 24 to the vertical position shown in solid lines in Fig. 9. The arm 164 now engages the pin 188 and moves it in the slot 190, to the right as viewed in Figs. 9 to 12. This moves the rod 178 in the direction of the arrow in Fig. 11, to tilt the bracket 174 about the pivot 176 and raise the brush roll 34. Simultaneously, the end 192 of the pin 188 is moved out of alignment with the lug 194a on the latch 130, or from the position shown in Fig. 10 to the position shown in Figs. 11 and 12. The latch 130 can now be displaced from the opening 76 by the latch 102, to free the slide 62 from the latch 130 and to lock the slide 62 and adapter 86 for joint movement from one position to another, according to whether the cleaner is to be used for attachment suction cleaning or attachment blowing. When the latch 130 is displaced by the latch 102 from the opening 76 in the side wall 78 of the slide 62, it assumes the position shown in Fig. 12 in which the lug 194a of the latch 130 is disposed in the

path of movement of end 192 of the pin 188. This prevents the return movement of the pin 188 and rod 178 by the action of the spring 169, regardless of the position of the handle 24. Therefore, the bracket 174 remains in its tilted position and the brush roll 34 remains raised.

When the cleaner is reconverted to its normal floor-nozzle cleaning position and the latch 102 and the adapter 86 are withdrawn, the latch 130 is biased by the spring 132 into the opening 76 in the slide 62 and out of the path of the stop 192. The spring 169, acting upwardly on the collar 170, tilts the bracket 174 in counterclockwise direction to lower the brush roll into contact with the surface being cleaned. The rod 178 and pin 188 now resume the position shown in Fig. 10.

Figs. 13 and 14

In Figs. 13 and 14, I show a still further modification of the invention in which I provide the embodiment illustrated in Fig. 1, a barrier with plate 196 carried by a lever 198. The lever 198 is pivoted at 200 to a bracket or other fixed portion on or of the cleaner body. The free end 202 of the lever 198 is movable vertically in a suitable opening 204. When the cleaner is used for floor-nozzle cleaning and with the handle in its normal range of operation, or at an angle of less than 90° from horizontal, the barrier plate 196 drops of its own weight into an opening 206 provided in the top walls of the passage 56 and the slide 62, to prevent the insertion of the adapter 86 into the slide 62. In order to be able to raise the barrier plate 196 out of the opening 206, I provide a lever 208 which is pivoted at 210 to a suitable bracket or other fixed portion, on or of the cleaner body. The lever 208 is so arranged that one end 212 thereof is adapted to engage the end 202 of the lever 198, while the other end 214 of the lever 208 is adapted to be engaged by a suitable formed extension arm 216 carried by the lower portion of the handle. The button 152 of the switch 150 is disposed in the path of movement of the lever 208, so as to be actuated thereby as hereinafter explained.

Figs. 13 and 14—Operation

When the cleaner is used for floor-nozzle cleaning, the levers 198 and 208 assume the position shown in dotted lines in Fig. 14, with the barrier plate 196 in the opening 206 to prevent insertion of the adapter 86. In this position, the lever 208 is out of contact with the button 152, the switch 150, is closed, and the solenoid 146 is energized to bring the brush roll 34 into contact with the surface to be cleaned. When it is desired to convert the cleaner to attachment blowing or attachment suction cleaning, it is necessary to raise the handle 24 to its vertical position to move the lever 208 by the extension arm 216 from the position shown in dotted lines, to the position shown in solid lines in Fig. 14. In so doing, the end 212 of the lever 208 presses down on the end 202 of the lever 198, thus raising the barrier plate 196 out of the opening 206. The adapter 86 can now be inserted, locked to the slide 62, and moved from one position to another in the manner above explained. In its solid line position, the lever 208 presses down on the button 152, thus opening the switch 150 to deenergize the solenoid 146 and permit the brush roll 34 to be raised by the spring 142 in the manner set forth in connection with Fig. 1.

Once the adapter 86 is inserted into the slide 62, it is impossible for the barrier plate 196 to

reenter the opening 206, and the levers 198 and 208 remain in about the position shown in solid lines in Fig. 14, regardless of the position of the handle 24. When the adapter 86 is withdrawn, the barrier plate 196 drops into the opening 206 by its own weight and the cleaner is again ready for floor-nozzle cleaning. As will be seen from Fig. 13, the barrier plate 196 is made relatively thick so as to more than counterbalance the weight of the levers 198 and 208 beyond the pivot 200.

The above described arrangement, whereby the sliding movement of the slide 62 controls the valve 58, the opening 138 and the opening 50, is claimed in my Patent No. 2,375,331. The integration of the adapter 86 with the slide 62, as by means of the lever 86, in order to effect such sliding movement of the slide 62, is claimed in my copending application Serial No. 485,185.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. A suction cleaner comprising a suction-creating device, a floor nozzle, a wall structure defining a passage, a valve for selectively connecting said nozzle or said passage to the suction side of said suction-creating device, a member movable into a first and second position in said passage, an adapter connected to an extension hose and insertable into said passage, latching means for integrating said adapter and said member for joint movement from one position to another within said passage, said adapter and said member being so constructed and arranged that the movement of said member from one to the other of its positions actuates said valve to shut said nozzle off from the suction side of said suction-creating device and to connect said adapter and extension hose thereto, a handle for propelling said cleaner, a movable barrier normally disposed in obstructing position operative to prevent integration of said adapter and said member, and means operable upon movement of said handle into a vertical position to remove said barrier from said obstructing position and permit integration of said member and said adapter.

2. The structure recited in claim 1, together with means urging said barrier for automatically returning said barrier to its obstructing position upon withdrawal of said adapter from said member and withdrawal of said handle from said vertical position.

3. A suction cleaner comprising a floor nozzle, a vertically adjustable agitator mounted therein and adapted to contact a surface to be cleaned, a suction-creating device, a wall structure defining a passage, a valve for selectively connecting said nozzle or said passage to the suction side of said suction-creating device, a member movable into a first and a second position in said passage, an adapter connected to a hose and insertable into said passage, latching means for integrating said adapter and said member for joint movement from one position to the other within said passage, said member being adapted upon being moved from one to the other of its positions to actuate said valve to shut said nozzle off from the suction side of said suction-creat-

ing device and connect said adapter and extension hose thereto, a handle for propelling said cleaner, a movable barrier normally disposed in obstructing position operative to prevent integration of said adapter and said member, means operable by movement of said handle into a vertical position to remove said barrier from said obstructing position and permit integration of said member and said adapter, and means operable by movement of said handle for elevating said agitator out of contact with said surface.

4. A suction cleaner comprising, a suction-creating device, a floor nozzle normally communicating with the suction side of said device, there being a first normally open outlet leading from the high-pressure side of said suction-creating device to the atmosphere, a wall structure defining a passage, a valve normally shutting said passage off from the low pressure side of said suction-creating device, there being a second outlet leading from the high-pressure side of said suction-creating device into said passage, a hollow open-ended slide movable in said passage to one intermediate and two end positions, said second outlet being normally closed by a wall of said slide, an adapter connected to a hose and insertable into said slide, means for latching said adapter and said slide for joint movement, said adapter and said slide being so constructed and arranged that the movement of said slide from its intermediate position to one of said end positions actuates said valve to shut off said nozzle from said suction device and connects said adapter to the low pressure side of said suction-creating device and the movement of said slide from said intermediate position to its other end position closes said first outlet and opens said second outlet to establish communication between said adapter and the high-pressure side of said suction-creating device, a barrier normally disposed in a position operative to obstruct movement of said slide from its intermediate position, a handle for propelling said cleaner, and means operable by movement of said handle to move said barrier from its obstructing position to permit movement of said slide.

5. The combination with a suction cleaner including a suction-creating device having a normally open outlet leading from the high-pressure side of said suction-creating device to the atmosphere, and a floor nozzle normally communicating with the suction side of said suction device, of means for converting said cleaner from floor-nozzle cleaning to attachment suction or attachment blowing including a passage, a valve for selectively connecting said passage or said nozzle to the suction side of said suction-creating device, a hollow open-ended slide disposed in said passage and having one intermediate and two end positions, means operable upon movement of said slide from said intermediate position to one of its end positions to connect said slide to the low pressure side of said suction-creating device, means operable by movement of said slide to its other end position to close said outlet and to connect said slide to the high-pressure side of said suction-creating device, locking means for retaining said slide in its intermediate position when the cleaner is used for floor-nozzle cleaning, a hollow adapter connected to an attachment hose and insertable into said slide, means carried by said adapter for disengaging said locking means and for integrating said slide and said adapter for joint movement from said intermediate position to either of said end positions, means

for retaining said slide and said adapter in either of said end positions, a handle for propelling said cleaner, a barrier normally disposed in an obstructing position operative to prevent integration of said adapter and said slide, and means operable by movement of said handle into a vertical position to remove said barrier from its obstructing position to permit integration of said slide and said adapter.

6. The structure recited in claim 1 together with means adapted, upon integration of said member and said adapter, to engage said barrier and to retain it out of its obstructing position regardless of the position of said handle.

7. A suction cleaner comprising a suction creating device, a floor nozzle normally communicating with the suction side of said suction creating device, a vertically movable agitator mounted in said nozzle, means for converting said cleaner from floor-nozzle cleaning to attachment operation, barrier means normally disposed in an obstructing position in which it prevents such conversion of said cleaner, a movable handle for propelling said cleaner, said agitator being in contact with a surface being cleaned when said cleaner is used for floor-nozzle cleaning, means operable in response to elevation of said handle into a substantially vertical position to move said barrier means to a nonobstructing position to permit such conversion of said cleaner, actuating means operable, in response to positioning of said

barrier means in its nonobstructing position, to raise said agitator out of contact with said surface, and means operable in response to conversion of said cleaner to attachment operation, to retain said barrier means in its nonobstructing position, in which said actuating means retains said agitator in its raised position, as long as said cleaner is converted to attachment operation, regardless of the position of said handle, said handle being freely movable independently of said barrier means.

8. A suction cleaner as recited in claim 1 and further including an agitator mounted in the floor nozzle, and means for raising the agitator in response to movement of the barrier to nonobstructing position.
